UNITED STATES PATENT OFFICE.

JOHN SCHROEDER, OF SAN FRANCISCO, CALIFORNIA, ASSIGNOR OF ONE-HALF TO LUDER RASCHEN, OF SAME PLACE.

PROPELLION OF VESSELS.

SPECIFICATION forming part of Letters Patent No. 443,168, dated December 28, 1890.

Application filed May 28, 1890. Serial No. 353,474. (No model.)

To all whom it may concern:

Be it known that I, JOHN SCHROEDER, a citizen of the United States, residing in the city and county of San Francisco, State of California, have invented an Improvement in the Propulsion of Vessels; and I hereby declare the following to be a full, clear, and exact description of the same.

My invention relates to improvements in the propulsion of vessels; and it consists in the employment of a chamber or chambers formed beneath and in the sides of the vessel diverging and opening backwardly through said sides, and a column of air forced through said passages, so as to press upon the body of water in which the vessel floats.

Referring to the accompanying drawings for a more complete explanation of my invention, Figure 1 is a side view of my device. Fig. 2 is a bottom view showing the arrangement of one chamber. Figs. 3, 4, and 5 show a series of chambers for a large vessel.

A is the hold of a vessel, having one or more chambers B formed beneath and in the sides. These chambers are preferably made diverging with the larger ends opening backwardly or toward the stern of the vessel, and C is a pipe or pipes, through which air under pressure is directed into these chambers. The air is compressed by any suitable pumping or air-compressing apparatus which will furnish a large volume of air under a small compression. This body of air is discharged into the chamber or chambers formed beneath the bottom of the vessel, and being forced backwardly within these chambers it impinges against the water in which the vessel floats, and thus serves to propel the vessel forward in this medium. When the vessel has a simple flat bottom, the chamber is made diverging from a point approximately near the stem and widening to the rear of the vessel, where the final opening or discharge is situated.

The bottom of this chamber may be inclosed or covered over partially or wholly, or it may be left open, the buoyant tendency of the air retaining it in the upper part of the chamber and preventing its escaping directly beneath the edges of the passage. If the vessel has a keel, the chamber or chambers will be made upon each side of the keel, diverging in the same manner as before described, but approximating as nearly as possible to the best form for the vessel's bottom, so as to prevent any undue retarding of the vessel on account of irregularities of surface at this point. If the vessel be large, it will be manifest that several of these diverging channels or chambers may be applied upon each side of the keel, the series extending from the stem toward the stern, and any one, two, or more of these chambers or passages may be supplied with air under pressure, so as to propel the vessel forward in a straight line or to assist in turning it.

Having thus described my invention, what I claim as new, and desire to secure by Letters Patent, is—

A vessel having a plural number of diverging channels or chambers formed in or beneath the bottom and arranged one behind the other from about stem to stern, said chambers having their larger ends opening rearward along each side of the vessel, pipes or passages through which air under pressure is discharged into said chambers to propel the vessel, and an air-forcing mechanism connected with said pipes, substantially as herein described.

In witness whereof I have hereunto set my hand.

JOHN SCHROEDER.
